UNITED STATES PATENT OFFICE

101,413

DESIGN FOR A TEXTILE FABRIC OR SIMILAR ARTICLE

Emile Ericson, Pelham, N. Y., assignor to Collins
& Aikman Corporation, Philadelphia, Pa., a
corporation of Delaware

Application June 9, 1936, Serial No. 63,168

Term of patent 14 years

To all whom it may concern:

Be it known that I, Emile Ericson, a citizen of the United States, a resident of Pelham, in the county of Westchester and the State of New York, have invented a new, original, and ornamental Design for a Textile Fabric or Similar Article, of which the following is a specification, reference being made to the accompanying drawing, forming part thereof.

The figure is a plan view of a piece of textile fabric showing my new design, the repeat of which is substantially contained between the two

horizontal dot-and-dash lines and the two vertical dot-and-dash lines.

The design comprises a woven textile fabric having a superposed duplex plaid arrangement, one of which plaid is dominating. The dominating plaid A consists of the configurations formed by short diagonal lines and filled in block, whereas the continuous lines form the plaid design B.

I claim:

The ornamental design for a textile fabric or similar article, as shown and described.

EMILE ERICSON.
